UNITED STATES PATENT OFFICE.

FREDERICK M. WHYTE, OF TARRYTOWN, NEW YORK, ASSIGNOR TO HUTCHINS CAR ROOFING CO., OF DETROIT, MICHIGAN, A CORPORATION OF MICHIGAN.

CAR ROOF.

Application filed September 16, 1918. Serial No. 254,204.

To all whom it may concern:

Be it known that I, FREDERICK M. WHYTE, a citizen of the United States of America, residing at Tarrytown, in the county of 5 Westchester and State of New York, have invented certain new and useful Improvements in Car Roofs, of which the following is a specification, reference being had therein to the accompanying drawings.

10 The invention relates to roofs for railway cars and more particularly to that type of roof in which metal roof sheets are employed.

The invention resides in the novel manner 15 of fastening the metal roof sheets upon the sub-structure so that weaving or other torsional strains of the sub-structure when the car is in service will not injure or destroy the metal roof sheets. The invention 20 further resides in the novel eaves connection for the metal roof sheets, in the novel ridge connection and in certain details of construction and arrangement of parts, as will more fully hereinafter appear.

25 In the drawings:

Figure 1 is a top plan view of a car roof, embodying the invention;

Figure 2 is a fragmentary sectional view longitudinally of the car;

30 Figure 2^a is a top plan view of the mullion joint cap;

Figure 3 is a partial cross-section through a car roof embodying the invention on the line $x-x$ of Fig. 2;

35 Figure 4 is a section transversely of the car at the ridge;

Figure 5 is a section at the ridge intermediate the mullions;

40 Figure 6 is a cross section at the eaves intermediate the mullions;

Figure 7 is a sectional view at the end of the car and longitudinally thereof;

Figure 8 is a fragmentary top plan view at the ridge;

45 Figure 9 is an end elevational view of the side of the car showing the eaves;

Figures 10 to 16 inclusive illustrate modifications;

50 Figures 10, 12, 14 and 16 being taken along a line equivalent to the line $x-x$ of Figure 2;

Figures 11 and 15 being end elevational views of the sides of the cars in Figures 10 and 14 respectively and showing the

eaves; Figure 13 being a perspective view 55 of a clip of the attaching section.

Referring to the one embodiment of the invention illustrated in Figures 1 to 9 inclusive, 1 designates the side plates of the car, 2 the end plate, 3 the side sheathing 60 and 4 the ridge pole. The sub-structure comprises the usual carlines 5 and purlins 6 upon which are arranged the roofing boards 7. While a wooden frame is shown in Figures 1 to 9 inclusive, the roof is applicable to steel frame cars or cars having frames of various constructions, the particular arrangement or type of frame being immaterial.

When the car is in service the roof sub-structure is subject to various torsional strains due to weaving or racking of the car body and among these strains is the bowing 70 of the side plates. To prevent the torsional strains being transmitted to the sheets, a 75 connection is provided at the eaves which will allow relative movement of the sub-structure in relation to the eaves ends of the roof sheets and allow bowing of the side plates without placing the roofing sheets 80 under strain or damage the eaves ends of the metal sheets but still providing a weather-proof joint between the side of the car and the metal roofing sheets.

In the construction in Figures 1 to 9 inclusive, the eaves ends of the roof sheet has a returned under-bent flange 8 which terminates in downwardly and outwardly extending portions forming an outwardly opening 90 pocket 9. This outwardly opening portion, or pocket, is positioned below the plane of the roof sheet and is arranged in a space, or chamber, 10 at the eaves of the car formed by terminating the roofing boards short of the car sides, as shown in Figures 1 to 9 inclusive, or else by rabbeting the boards at the eaves. Secured to the side of the car is a flashing 11 having a substantially horizontal portion 12 extending underneath the ends of the roof sheets. At the inner end this flashing has an upwardly extending flange 13 rebent downwardly at 14 and then extending outwardly to form a flange 15 engaging the outwardly extending flanges 16 of the roofing sheets. The flashing 11 extends from end to end of the car either in a continuous piece or by being formed of a plurality of overlapping sections, as will be readily un- 100

derstood. The outwardly opening pocket 9 at the eaves end of the sheet is engaged by an eaves attaching section. This section in the construction shown in Figures 1 to 9 inclusive comprises a wooden strip 17 that has an inwardly extending portion or tongue 18 fitting the outwardly opening pocket 9. The strip 17 is attached to the car frame as by a plurality of metal straps or brackets 19 having downwardly extending portions secured to the frame by bolts 20 and having inwardly extending portions secured to the wooden strip and preferably countersunk therein. The inner end of the outwardly opening pocket 9 is spaced from the upward rebend of the flashing strip a sufficient distance to provide for all normal weaving or racking that the car sub-structure may have.

The wooden attaching section 17 extends uninterruptedly either as a single member or as a plurality of members from end to end of the car. This attaching section instead of being formed of wood may be formed of a sheet metal member 20 (see Figures 10 and 11). The member 20 is illustrated as in the form of an outwardly opening channel, the legs of which have depressions 21 fitting sockets 22 in the securing strips or bracket 23. These depressions form pockets for receiving the heads 24 of rivets 25 that secure the bracket to the member 20. 26 is an inward projection or tongue engaging the outwardly opening pocket 9 of the roofing sheet.

Instead of the attaching section extending continuously from end to end of the car, it may be formed of a plurality of separated members or clips 27, as illustrated in Figures 12 and 13.

In the drawings the roofing sheets 28 are shown of the type that extend from ridge to eaves. These roofing sheets are positioned between mullions or battens 29 arranged in spaced relation upon the roofing boards and secured thereto. At the sides the roofing sheets have flanges 30 terminating in inwardly and downwardly extending portions 31. The vertical flanges 30 of the roof sheets are spaced from the sides of the mullions, as shown in Figure 2, so that relative movement of the sub-structure and the sheets will be permitted. Making the joint between the sides of adjacent sheets and covering the mullions are joint caps 32 which have downwardly extending side flanges 33 connected by bends 34 with upwardly and inwardly extending flanges 35. The flanges of the cap are spaced from the flanges at the sides of the sheets so that relative movement between the cap and the sheets is permitted. At their ends the mullion caps have closures 36 bent downwardly and then inwardly as indicated at 37, the inwardly extending portions 37 being arranged beneath the rebent flange 8 of the roofing sheets and

terminating in downwardly extending flanges 38. The portions 37 and 38 of the closure 36 have their outer side edges arranged within the outwardly opening pocket 9 of the roofing sheet, and as the pocket 9 does not extend underneath the mullions, the flanges 37 and 38 assist in forming a weather-proofing connection at the end of the mullion cap. The connection between the attaching section and the outwardly opening pocket acts to hold the roofing sheets down upon the roofing boards at the eaves and since the closure for the mullion cap extends underneath the rebend of the roofing sheets, the eaves end of the mullion cap is secured to the roof against vertical movement. The engagement between the downwardly bent portion of the mullion cap and the attaching section limits the outward movement of the mullion cap.

At the ridge the sheets have vertically extending flanges 39 terminating in horizontal portions 40. The flanges 39 of the sheets upon one side of the car are spaced from the flanges 39 of the sheets upon the other side of the car (see Figure 5). Embracing the flanges at the ridge ends of the sheets are ridge caps 41. These caps have downwardly extending sides 42 having at their lower ends foot flanges 43 that terminate in vertical portions 44. The vertical portions 44 are spaced from the vertical flanges 39 so as to allow the roofing sheets to be free to move at the eaves. The caps 41 are of a length to sit between the side flanges 30 of the roofing sheets and are held in place by ridge corner caps 45 that are secured in the usual manner to the ridge pole by means of bolts 46.

At the ends of the car roof, the wooden strips 58 are provided, over which the metal weather-proofing caps 59 extend (see Fig. 7). These caps have at their outer edges the depending flanges 60 overlapping the side sheathing 3 at the ends of the car and are secured to the endplates 2 by the bolts 61. The inner edges of the caps have a loose hooked engagement with the side flanges of the roofing sheets 28 similar to that between the mullion caps 32 and the roofing sheets.

From the foregoing description it will be seen that in the particular type of roof illustrated in the drawings the roofing sheets are held from outward movement by the attaching section and that the latter also holds the sheets down upon the roof against vertical movement. The attaching section, however, since it is not connected other than by a sliding engagement with the outwardly opening pocket at the eaves ends of the sheets does not interfere with a free relative movement of the roofing sheets. As the attaching section extends longitudinally of the car at the eaves and is normally arranged in a straight line it acts to maintain the roof

sheets "in square" upon the car. As will be noted the inner face of the attaching section is of a form to co-operate with the outwardly opening pocket of the roofing sheets to prevent the inner edge of the attaching section from cutting or wearing through the pocket portion. In the forms of the attaching section illustrated in the drawings, the inner edge of the inwardly projecting tongue of the attaching section has a comparatively wide flat face and the rear wall of the pocket portion is of a similar contour.

Where the continuous wooden strip 17 is employed, it preferably is provided with a plurality of grooves 47 in its underface to prevent any moisture collecting on the flashing. The number of these grooves may vary as desired. Although the construction shown in Figures 10 and 11 is not illustrated as provided with grooves in the bottom face thereof, the channel member 20 may, if desired, have its lower leg provided with grooves similar to those shown in connection with the member 17.

In the construction illustrated in Figures 12 and 13 the flashing strip 48 is provided with a raised portion 49 which engages the underside of the outwardly opening pocket of the roof sheet. The rear end of the flashing strip terminates in a rebent vertically extending flange 50. In Figures 14 and 15 a different construction of attaching clip is shown, this clip 51 being connected to the sub-structure by a single bracket 52. The flashing 53 extends underneath the clip and the outwardly opening pocket of the roofing sheet and terminates in a vertical flange 54. While the particular eaves attaching sections shown in the drawings are desirable, it is to be understood that various modifications can be made without departing from the invention.

With the structure described, while the attaching section acts to normally hold the sheets "in square" upon the car, in case of undue strain resulting in the sheets being moved out of square in relation to the sub-structure, the eaves connection will not in any way strain or tear the eaves end of the sheet. Normally the connection at the eaves will provide for all relative movements between the roof sub-structure and the sheets and, if there is a bowing of the side plates, the attaching section can move outwardly in the pocket at the eaves ends of the sheets and this movement will not carry the roof sheets with it. In case of abnormal movement, additional play is provided at the ridge, since, as before described, the ridge connection is such as to allow relative movement between the ridge cap and the ridge ends of the sheets. If the ridge ends of the sheets are brought into engagement with the ridge caps, there will be no tendency for the flanges 44 to shear the flanges 39 since these

parts are comparatively wide and extend substantially parallel to one another.

Instead of providing a space between the flashing and the inner end of the pocket portions of the roofing sheets, so as to permit play at the eaves, as described, the rear portion of the flashing may be arranged in close proximity to the end portion, as shown in Figure 16. In this figure, 55 designates the flashing, 56 the upwardly extending rear portion thereof and 57 the outwardly opening pocket portion of the roofing sheet. The remaining parts will be readily understood, from previous description.

With the construction shown in Figure 16, the play of the sheets cross-wise of the car is permitted by the ridge connection, which is of the same arrangement as shown in Figures 1 to 9 inclusive.

In each of the constructions described, the roofing sheets and the mullion cap are held against vertical movement by the attaching section and also against outward movement. To assemble the parts, the flashing is first applied to the car, the roofing sheets placed in position and then the mullion caps engaged with the roofing sheets. The attaching section is then positioned in place within the outwardly opening pocket portions of the roofing sheets and secured to the car.

What I claim as my invention is:

1. In a car roof the combination of a sub-structure, a plurality of metal roofing sheets arranged thereover, the eaves ends of said roofing sheets terminating in outwardly opening pockets, joint caps for the side edges of the roofing sheets having portions extending within said outwardly opening pockets and an eaves attaching section for the outwardly opening pocket portion of the sheet.

2. In a car roof the combination of a sub-structure, a plurality of metal roofing sheets arranged thereover having outwardly opening pockets at their eaves ends, joint caps for the side edges of the sheets having downturned end portions terminating in inwardly extending flanges arranged within the outwardly opening pockets of the roof sheets and means engaging the outwardly opening pockets of the roofing sheets for loosely securing the eaves ends of the roofing sheets upon the sub-structure.

3. In a car roof the combination of a sub-structure, a plurality of metal roofing sheets arranged thereover, having outwardly opening pockets at their eaves ends positioned below the plane of the roofing sheets; joint caps for engaging the side edges of the sheets having downturned end portions terminating in an inwardly extending flange, said flange having a downwardly and outwardly extending portion positioned within the outwardly opening pockets of the roofing sheets and an attaching section secured to the sub-

structure at the eaves and arranged within the outwardly opening pocket portion of the roofing sheets.

4. In a car roof the combination of a sub-
5 structure, a plurality of metal roofing sheets
arranged thereover, means loosely engaging
the eaves ends of the sheets for limiting the
outward movement of the sheets, said means
10 permitting movement of the sheets in all
directions in their planes and being free to
move outwardly in relation to the sheets and
a flashing strip for the sub-structure at the
eaves arranged beneath said roofing sheets.

5. In a car roof the combination of a sub-
15 structure, a plurality of metal roofing sheets
arranged thereover, having outwardly open-
ing pocket portions positioned beneath the
plane of the roofing sheets, joint caps for
the sides of the sheets, having downturned
20 end portions terminating in inwardly ex-
tending flanges arranged within said pocket
portions, a flashing strip for the sub-struc-
ture at the eaves extending beneath said
pocket portions and having an upwardly ex-
25 tending flange at its inner end spaced from
the pocket portions and an eaves attaching
section engaging said pocket portions.

6. In a car roof the combination of a sub-
30 structure, a plurality of metal roofing sheets
arranged thereover, having outwardly open-
ing pocket portions positioned beneath the
plane of the roofing sheets, joint caps for the
sides of the sheets, having downturned end
35 portions terminating in inwardly extending
flanges arranged within said pocket portions,
a flashing for the sub-structure at the eaves
extending beneath said pocket portion hav-
ing a portion engaging the bottom of said
40 pocket portions and extending substantially
parallel therewith and an eaves attaching
section engaging said pocket portions.

7. In a car roof the combination of a sub-
45 structure, a plurality of metal roofing sheets
arranged thereover, having outwardly open-
ing pocket portions positioned beneath the
plane of the roofing sheets, joint caps for the
sides of the sheets, having downturned end
50 portions terminating in inwardly extending
flanges arranged within said pocket portions,
a flashing for the sub-structure at the eaves
having an upwardly extending flange at its
inner end spaced from the inner end of the
55 pocket portion and terminating in a down-
wardly and outwardly extending flange, the
outwardly extending flange projecting be-
neath the pocket portions and an attaching
section secured to the sub-structure at the
60 eaves positioned above said flashing strip and
engaging said pocket portions.

8. In a car roof the combination of a sub-
65 structure, a plurality of metal roofing sheets
arranged thereover and extending from
eaves to ridge, mullions between which said
sheets are arranged, mullion caps for the
joints between the mullions and the sheets,

said sheets having outwardly opening pocket
portions arranged therebeneath and said
caps having downturned end portions termin-
inating in inwardly extending flanges engag-
ing the outwardly opening pocket portions, 70
a flashing for the sub-structure at the eaves
extending beneath said outwardly opening
pocket portions, an attaching section engag-
ing the outwardly opening pocket portions
of the roofing sheets and limiting the out-
ward movement of the sheets, said attaching
section being free to move outwardly in re-
lation to the sheets and ridge caps engaging
the ridge ends of the sheets but permitting
relative movement of the sheets and ridge 80
caps crosswise of the car.

9. In a car roof the combination of a sub-
structure, a plurality of metal roofing sheets
arranged thereover, having outwardly open-
ing pocket portions, joint caps for the side 85
edges of the sheets having downturned end
portions bent inwardly and terminating in a
downwardly extending flange and an attach-
ing section at the eaves engaging the pocket
portion of the sheets and the downturned 90
flange portion of the cap.

10. In a car roof the combination of a sub-
structure, a plurality of metal roofing sheets
arranged thereover having rebent under-
95 bent flanges terminating in outwardly open-
ing pocket portions, joint caps for the side
edges of the sheets having downturned end
portions provided with extensions projecting
within said pocket portions and terminating
100 in downturned flanges and an attaching sec-
tion at the eaves engaging the outwardly
opening pocket portion and the downturned
flange portions of the joint caps, said attach-
ing section acting to limit the outward move-
ment of the sheets and the caps and acting 105
to hold the sheets against vertical movement.

11. In a car roof the combination of a sub-
structure, a plurality of metal roofing sheets
arranged thereover, having outwardly open-
ing pockets at their eaves ends positioned be-
110 low the plane of the roofing sheets, joint
caps for engaging the side edges of the sheets
having downturned end portions terminat-
ing in an inwardly extending flange, said
flange having a downwardly and outwardly 115
extending portion positioned within the out-
wardly opening pockets of the roofing sheets
and an attaching section secured to the sub-
structure at the eaves and arranged within
the outwardly opening pocket portion of the 120
roofing sheets and joint caps.

12. In a car roof the combination of a
sub-structure, a plurality of metal roofing
sheets arranged thereover having their outer
ends rebent underneath the sheets, the re-
bent ends having flange portions and an
eaves attaching section positioned beneath
the rebent ends and having a portion ar-
ranged in the path of said flanges, there
being relative movement permitted between 125
130

5 said flanges and attaching section, and a flashing strip for the sub-structure at the eaves extending below said outwardly opening pocket portion.

13. In a car roof the combination of a sub-structure, a plurality of metal roofing sheets arranged thereover, having their outer ends rebent underneath the sheets and a wood eaves attaching section arranged beneath the rebent eaves ends of the sheets and engaging and supporting said rebent ends, said section being free to move outwardly relative to the sheets.

14. In a car roof the combination of a sub-structure, a plurality of metal roofing sheets arranged thereover having their outer ends rebent underneath the sheets, joint caps for the sides of the sheets having portions engaging the sheets and acting to prevent vertical movement of the sheets, said caps having rebent flanges at their outer ends terminating in outwardly opening pocket portions and an eaves attaching section engaging said pocket portions of the caps.

15. In a car roof, the combination of a sub-structure, of a plurality of metal roofing sheets arranged thereover, the eaves ends of said roofing sheets terminating in outwardly opening pockets, and joint caps for the side edges of said roofing sheets having portions extending within the outwardly opening pockets of said roofing sheets.

16. In a car roof, the combination of a sub-structure, a roofing sheet having a depending flange at an eave of the roof, and a bearing for said flange of sufficient depth to form a non-shearing stop to limit the outward movement of said roofing sheet, said bearing being free to move outwardly relative to said roofing sheet.

17. In a car roof, the combination of a sub-structure, a roofing sheet having a depending flange at an eave of the roof, and a bearing for said flange of sufficient depth to form a non-shearing stop to limit the outward movement of said roofing sheet, said

bearing being arranged beneath said roofing sheet and being free to move outwardly relative thereto.

18. In a car roof, the combination of a sub-structure, a plurality of metal roofing sheets arranged thereover, the eaves ends of said sheets having outwardly opening portions with walls extending transversely of said roofing sheets, and means engaging in said outwardly opening portions and having bearings for said transversely extending walls of sufficient depth to form non-shearing stops to limit the outward movements of said roofing sheets, said means being free to move outwardly relative to said roofing sheets.

19. In a car roof, the combination of a sub-structure, a plurality of roofing sheets arranged thereover, the eaves ends of said sheets having outwardly opening portions with walls extending transversely of said roofing sheets and eaves attaching sections positioned beneath said roofing sheets and engaging in said outwardly opening portions, said sections having bearings for said transversely extending walls of sufficient depth to form non-shearing stops to limit the outward movements of said roofing sheets, said sections being free to move outwardly relative to said roofing sheets.

20. In a car roof, the combination of a sub-structure, a plurality of roofing sheets arranged thereover and having their outer ends re-bent underneath the sheets, the rebent ends having flange portions extending transversely of the sheets, and an eaves attaching section positioned beneath the rebent ends and having a bearing portion arranged in the path of said flange portions of sufficient depth to form non-shearing stops to limit the outward movements of the sheets, said eaves attaching section being movable relative to said flange portions.

In testimony whereof I affix my signature.

FREDERICK M. WHYTE.
